229,502

DRIVING PAD RISER FOR DISC FLOOR SURFACING MACHINE

James E. Thielen, New Brighton, Minn.
(2501 Hudson Road, St. Paul, Minn. 55101)

Filed Mar. 1, 1971, Ser. No. 120,001

Term of patent 14 years

Int. Cl. D15—99

U.S. Cl. D37—1

FIG. 1

FIG. 2

FIG. 3

FIG. 4

FIG. 1 is a perspective view of the driving pad riser for disc floor surfacing machine of the invention;

FIG. 2 is a top plan view thereof;

FIG. 3 is a bottom plan view thereof;

FIG. 4 is a front elevational view thereof with parts broken away as indicated by line 4—4 in FIG. 2 to show details of the design, the rear being a mirror image of the front.

I claim:

The ornamental design for a driving pad riser for disc floor surfacing machine, substantially as shown and described.
